UNITED STATES PATENT OFFICE.

EUGENE BRISBIN, OF WESTON, OHIO.

WIRE-FENCE POST.

SPECIFICATION forming part of Letters Patent No. 338,030, dated March 16, 1886.

Application filed April 17, 1885. Serial No. 162,707. (No model.)

To all whom it may concern:

Be it known that I, EUGENE BRISBIN, of Weston, in the county of Wood and State of Ohio, have invented a new and Improved 5 Wire-Fence Post, of which the following is a full, clear, and exact description.

The object of my invention is to provide a new and improved post for wire fences, which post is light, strong, and durable.

10 The invention consists in the peculiar construction and arrangement of parts, as hereinafter fully described, and pointed out in the claim.

Reference is to be had to the accompanying 15 drawings, forming a part of this specification, in which similar letters of reference indicate corresponding parts in both the figures.

Figure 1 is a side view of my improved wire-fence post. Fig. 2 is a plan view of the base.

20 The flat base A, made of steel or malleable iron, is provided with a central aperture, B, for receiving a tenon on the lower end of a flat upright or post, C, made of steel or malleable iron, and having its sides parallel with the side edges of the base. In each end of the base A one or two apertures, D, are formed. The post or upright C has a series of inwardly and downwardly inclined slits, E, in one edge, and vertical slots F at the inner ends of the

25 30 said slits E. At the middle of the post two apertures, G, are provided, one above the other, and serve to receive the upper bent ends

of the brace-rods H, which are bent directly above the base and have their lower ends passed through apertures D. They have spurs 35 J on their ends, which spurs are forced into the ground and hold the base and prevent slipping. The fence-wires are slipped through the slits E into the slots F.

I am aware that fence-posts have been provided with inclined slits on their edges extending to apertures in the posts. 40

I am also aware that posts have been braced by inclined braces extending from the base-plate to the posts; and I am further aware 45 that inclined brace-wires have been extended below the base-plate and provided with anchors; and I therefore do not claim such inventions.

Having thus described my invention, I claim 50 as new and desire to secure by Letters Patent—

The combination, with a base, A, having a central aperture, B, and end apertures, D, of the post C and the rods H, having their upper ends held on the post and their lower ends 55 bent above the base-plate A to form offsets, and prongs J, which prongs J are forced through the base into the ground, substantially as herein shown and described.

EUGENE BRISBIN.
